UNITED STATES PATENT OFFICE.

THOMAS F. ROWLAND, JR., OF NEW YORK, N. Y.

FLANGING-MACHINE.

SPECIFICATION forming part of Letters Patent No. 761,918, dated June 7, 1904.

Application filed December 12, 1903. Serial No. 184,880. (No model.)

To all whom it may concern:

Be it known that I, THOMAS F. ROWLAND, Jr., a citizen of the United States, and a resident of the borough of Brooklyn, city of New York, county of Kings, and State of New York, have invented certain new and useful Improvements in Flanging-Machines, of which the following is a specification, taken in connection with the accompanying drawings.

10 This invention relates to flanging-machines, and relates especially to machines for forming the end flanges on corrugated furnaces.

In the accompanying drawings, Figure 1 is a plan view of a flanging-machine embodying 15 this invention. Fig. 2 is a longitudinal vertical section of the same. Figs. 3 and 4 are partial transverse vertical sections showing the parts in different positions.

20 In the embodiment of this invention shown in the drawings a rigid frame is formed for the operating parts of the machine, this frame comprising the bed 1 and the pillar 17. This pillar is adapted to support the power-actuated flanging-head 24, which preferably has a fixed 25 line of movement, this line of movement being angularly disposed with relation to the bed, as indicated in the drawings. This head is shown secured to the piston 20, operating within the cylinder 2, this cylinder being provided with a suitable stuffing-box 23 at its lower end and being operated by fluid under pressure—such as water, steam, or other fluid—which may be admitted as desired through the port 21 to the space 25 above the piston or 35 through the port 22 to raise the flanging-head.

Suitable means are provided on the bed to support a furnace, so that it will coöperate with the flanging-head. In the drawings the corrugated furnace 50 is shown as rotatably 40 supported, resting upon a series of antifriction supporting-rolls 5, which may be revolvably mounted upon suitable shafts 4, extending longitudinally of the machine at either side of the same. These shafts are preferably 45 laterally adjustable and for this purpose may be rigidly secured in the blocks 11. Each of these blocks may be adjusted, as shown in Fig. 1, by turning the screw 12, engaging the block and swivelingly mounted in the lug 13, 50 and in this way the supporting means may be

adjusted to accommodate furnaces of different size. Aliners are preferably employed to secure the exact longitudinal position of the furnaces on the machine. Aliners in the form of rolls 6 may be used, and, as indicated, each 55 of these aliners is rotatably mounted in the sleeve 14, loosely engaging the shaft 4. Each alining-roll and its sleeve may be thus angularly and longitudinally adjusted so as to properly coat with the furnace and may be rigidly secured in desired position by the bolt 31, which clamps the sleeve to its shaft. In order to more securely maintain the furnace in position and prevent the furnace end from rising, a holding-lever 10 may be employed, 65 this lever being preferably pivoted about the pin 29 in the standard 9, which is secured to the bed. This lever is preferably provided at its forward end with the holding-roll 7, which engages the rear end of the furnace. 70

It is desirable in operating this flanging-machine that the anvil which supports the furnace and which coöperates with the flanging-head be rigidly supported at all times and also that it be of adjustable height, so as to 75 form flanges at different distances from the wall of the furnace. This is of special importance where the end flange of the furnace is not concentric with the body of the same, but has an irregular shape—such, for instance, 80 as is indicated in the drawings—this type of furnace being quite common in marine work. To accomplish this purpose, the anvil 3 may be given any form, so as to have a varying height at various parts of the same, and may 85 be formed as indicated in Figs. 3 and 4, and this anvil may be mounted to be adjusted transversely of the machine by any suitable means, so that the operative portion of the anvil adjacent the flanging-head is of the 90 height desired. As indicated, the anvil 3 is formed with the guide 27, which coöperates with a suitable groove in the bed of the machine, and this anvil is engaged by the adjusting-screw 18, swiveled in the lug 15, formed 95 on the projecting portion 14 of the bed. This screw may be operated by a suitable wheel 16 or by any other means, so as to properly adjust the varying-height anvil and to rigidly hold it in position. The support 8 may be 100

used adjacent the anvil and properly secured to the bed, so as to support the adjacent face of the anvil.

In operating this machine the furnace 50, which may have the flange 51 roughly formed at one end of the same, is mounted upon the supporting-rolls, the aliners being properly adjusted and fixed in position. The flange may then be heated in whole or in part to the desired extent, and the varying-height anvil is moved transversely, so as to support the flange 51 at the desired height. The flanging-head 24 is then operated hydraulically or in any other way to finish one portion of the flange by firmly pressing it down against the side of the anvil 3. The furnace is then rotated by hand or by any other suitable means, and as it is rotated the anvil height is adjusted by the means indicated, the flanging operation being continued, so that each portion of the flange 51 is operated upon and the flange is finished throughout its entire extent. The range of adjustment of the anvil 3 necessary for forming the flange shown in the drawings is indicated in Figs. 3 and 4.

It is of course understood that many modifications in the form, proportion, and number of parts of this machine may be made by those familiar with this art. Furthermore, parts of the same may be used without employing the whole, and parts may be used in connection with other devices without departing from the spirit of this invention or losing the advantages of the same. I do not, therefore, desire to be limited to the details of the disclosure which has been made in this case; but

What I claim as new and what I desire to secure by Letters Patent is set forth in the appended claims:

40 1. In flanging-machines, adjustable longitudinal shafts carrying supporting - rolls,

liners coöperating with said shafts to rotatably support a furnace, a holding-lever adjacent said aliners to hold said furnace in position, a transversely -adjustable rigidly-supporting anvil of varying height to support a flange on said furnace, an angularly-arranged cylinder and a flanging-head operated by said cylinder and coöperating with said anvil to form said flange.

2. In flanging-machines, longitudinal shafts carrying supporting-rolls, aliners to rotatably support a furnace an anvil of varying height, means to transversely adjust said anvil to bring various parts of the same into operative position, said anvil being rigidly supported during the operation of the machine and a power-actuated flanging-head coöperating with said anvil.

3. In flanging-machines, a frame, means mounted on said frame to support a blank, a power-actuated flanging-head mounted on said frame and an anvil movably mounted in a transverse guide in said frame to bring the various parts of said anvil into coöperation with said head and adjust the height of said anvil with respect to said head while rigidly supporting said anvil in operative position.

4. In flanging-machines, a frame, machines mounted on said frame to rotatably support a furnace, a power - actuated flanging - head mounted on said frame and having a fixed line of movement, an anvil of varying height mounted in a transverse groove in said frame and means to adjust the position of said anvil to bring the various parts of the same into co-operation with said head and to hold said anvil in operative position.
